UNITED STATES PATENT OFFICE.

HOWARD G. McILVRIED, OF McCANDLESS TOWNSHIP, ALLEGHENY COUNTY, PENNSYLVANIA, ASSIGNOR TO AMERICAN SHEET AND TIN PLATE COMPANY, OF PITTSBURGH, PENNSYLVANIA, A CORPORATION OF NEW JERSEY.

STRIP-TRANSFER APPARATUS.

Application filed July 14, 1927. Serial No. 205,669.

This invention relates to transfer apparatus and, while not limited thereto, relates more particularly to apparatus for transferring or switching metal strips from the run-out table, and has for its object the provision of a transfer apparatus of this class which operates automatically.

Another object is to provide a transfer apparatus of the class described which may be applied to a standard run-out table and which may be rendered operative or inoperative, as desired, so as to either intercept the strips from the mill run-out table, or to permit said strips to run past said apparatus uninterrupted.

A further object is to provide a transfer apparatus having the novel construction, design, and combination of parts hereinafter described, and illustrated in the accompanying drawings.

In the drawings—

Figure 1 is a plan of a mill having the transfer apparatus of this invention applied thereto.

Figure 2 is an enlarged plan of a portion of the mill run-out table having the transfer apparatus applied thereto.

Figure 3 is a side elevation thereof.

Figure 4 is a transverse sectional elevation taken through the mill run-out table directly in front of one of the transfer apparatus.

Figure 5 is a sectional elevation taken on the line V—V of Figure 4.

Figure 6 is a fragmentary plan illustrating a modified construction in which single rollers are substituted for the pinch rollers in the transfer apparatus.

Figure 7 is a plan view similar to that of Figure 1 except that take-up reels are substituted for the hot beds.

Referring more particularly to the drawings, the letter A designates the finishing stand of rolls of a rolling mill adapted to produce a finished thin flexible strip of considerable length. The finished strip passes from the roll stand A onto the conveyer or run-out table 2 which is of the usual construction, having a top apron plate 3 and conveyer rollers 4.

A plurality of hot beds 5 are arranged at spaced intervals along the one side of the mill run-out table 2 and extend at substan-

tially right angles thereto. A hot bed run-out table 6 is provided at the center of each of the hot beds 5 and is adapted to receive the rolled strips from the mill run-out table 2. The hot bed run-out tables 6 are of the usual construction and are provided with conveying rollers at spaced intervals.

The hot beds 5 and table 6 are on a higher level than the mill run-out table 2 and each of the tables 6 are connected with the table 2 by a transfer apparatus B adapted to intercept the strips being conveyed along the table 2, and direct said strips onto the table 6.

The transfer apparatus B each comprise a housing 8 which bridges the mill run-out table 2 and supports a guide plate 9, the lower end of which is in line with the mill run-out table 2, while the upper end is in line with the hot bed run-out table 6. That is, the guide plate 9 is twisted in the form of a spiral for 180 degrees more or less through its length and is curved toward the hot bed run-out table side of the mill run-out table so that its delivery end is at right angles to its receiving end, and strips fed along the guide plate will be forced to travel through a spiral path so as to be bent across their transverse axis and delivered at right angles to the mill run-out table 2.

A plurality of pairs of pinch rollers 12 are journaled on the housing 8 and serve to feed the strips along the guide plate 9. The guide plate 9 is recessed to permit the bottom roller of each pair of pinch rollers to extend therethrough in engagement with the other roll of the pair.

The pinch rollers 12 may be driven by separate motors such as the motors 13 shown, or may have self contained motors, as desired.

If desired, the pinch rollers 12 may be omitted and the guide plate 9 may be made continuous with single rollers 12^a substituted for the pinch rollers 12 and bearing against the guide plate 9 to feed the strips along the plate 9, shown in Figure 6. In this case the strips will be fed between the rollers 12^a 100 and the plate 9.

The mill run-out table is provided with a pair of pinch rollers 14 adjacent each of the transfer apparatus B to feed the strips

onto such apparatus, and the hot bed run-out tables 6 are each provided at their entrance ends with a pair of pinch rollers 15 to receive the strips from the transfer apparatus B.

5 Each of the transfer apparatus B is provided with a switching mechanism for intercepting the strips being conveyed along the mill run-out table 2, which mechanism 10 comprises a frame 16 slidably mounted for vertical movement in guideways 17 on the housing 8 and adapted to be operated by a connecting rod 17^a which has its one end connected to the frame 16 and its other end 15 connected to the crank portion 18 of a crank shaft 19 journaled in bearings 20 on the housing 8. The shaft 19 is connected to a drive shaft 21 which is operated by a motor 22 through a standard speed reducing 20 gearing unit indicated at 23.

The switching frame 16 is adapted to enter a recess 25 in the mill run-out table 2, and is provided at its lower end with an apron plate segment 26, adapted, when the 25 frame is in its upper extreme position, to form a continuation of the apron plate 3 of the mill run-out table 2, so that the strips being conveyed may pass uninterrupted through the transfer apparatus. A switch 30 plate 27 is mounted in the frame 16 at a point materially above the apron plate segment 26 so as to clear the run-out table 2 when the frame 16 is in its upper extreme 35 position, and adapted to have its forward edge moved into the plane of the apron plate 3 of the table 2 and to have its rear edge moved into the plane of the guide plate 9 when the frame 16 is in its lower extreme 40 position, so as to intercept the strips being conveyed along the mill run-out table 2 and direct said strips onto the guide plate 9 where they will be engaged by the pinch 45 rollers 12 and fed through the transfer apparatus B and onto the hot bed run-out table 6.

50 In operation it is only necessary for the operator to lower the switching frame 16 of the transfer device connected to which ever one of the hot beds 5 he desires to 55 strips being rolled to be piled on, and to raise the frames 16 of the other transfer devices between the mill and the one to be operated. The lowering of the selected switching frame 16 will move the switch 60 plate 27 of the switching frame into position to intercept the strips being conveyed along the mill run-out table 2 and direct the strips through the transfer device B, which will in turn feed the strips onto the hot bed run-out table 6.

65 When the hot bed becomes filled, or for any reason it is desired to direct the strips onto one of the other hot beds 5, it is only necessary for the operator to raise the switching frame 16 previously lowered and

to lower the switching frame of the transfer mechanism connected with the other hot bed, so that the switch plate 27 of this last switching frame will intercept the strips.

70 While I have shown and described the transfer apparatus B as delivering the strips at substantially right angles, and with their guide plates 9 twisted in the form of a spiral for approximately 180 degrees, it will be expressly understood that I do not 75 wish to be limited to such angle of delivery since the guide plates 9 may be twisted either more or less than 180 degrees and, therefore, deliver the strips at other angles than at right angles to the run-out 80 table. It will be, of course, understood that if the transfer apparatus B delivers the strips at other than right angles the hot beds 5 will also be arranged at a similar angle to receive the strips.

85 It will also be understood that while I have shown the hot beds 5 as located above the run-out table 2, such construction is only illustrative and that the hot beds may be located below the run-out table if desired 90 or at any elevation desired, without departing from the scope of my invention.

95 In Figure 7 I have shown a plan of a modified form of mill in which the hot beds 5 are omitted and the hot bed run-out tables 6 are materially shortened and lead to power operated reels 30 which are adapted to reel up the rolled hot strips.

100 While I have shown and described one specific embodiment of my invention, it will be understood that I do not wish to be limited thereto, since various modifications may be made in the general combination and in structural details, without departing from the scope of my invention as defined in the 105 appended claims.

105 I claim—

110 1. The combination with a rolling mill for rolling flexible strips of metal and having a run-out table for conveying said strips away from said mill, of a plurality of other tables arranged at an angle to said first named table, and means at the junction points of said tables adapted to intercept the strips being conveyed along said run-out 115 table and turn and twist said strips through a spiral path and direct said strips onto said second named tables, said means being selective so that said strips may be directed onto any selected one of said second named 120 tables.

125 2. The combination with a rolling mill run-out table, of a switching mechanism adapted to intercept the rolled articles passing along said table from said mill, said means including a movable switch frame, a switch member on said frame adapted to intercept the articles passing along said table in one position of said frame, and an apron member on said frame adapted to 130

form a continuation of the top apron plate of said table in the other position of said frame.

3. The combination with a rolling mill 5 run-out table, of a switching mechanism adapted to intercept the rolled articles passing along said table from said mill, said means comprising a housing, a guide plate in said housing for guiding the articles 10 being switched from said table, a movable switch frame, a switch plate on said frame adapted to form a continuation of said guide plate and to intercept the articles 15 passing along said table in one position of said frame, and an apron plate on said frame adapted to form a continuation of the top apron plate of said table in the other position of said frame.

4. The combination with a rolling mill 20 for rolling flexible strips of metal and having a run-out table for conveying the strips away from said mill, of at least one other table arranged at an angle to said first named table, and a switching mechanism 25 adapted to intercept the rolled strips passing along said run-out table from said mill and direct said strips onto said second named table, said switching mechanism including a movable switch frame, a switch member on 30 said frame adapted to intercept the strips as they are conveyed along said run-out table in one position of said frame, and an apron member on said frame adapted to 35 form a continuation of the top apron plate of said run-out table in the other position of said frame.

5. The combination with a rolling mill 40 for rolling flexible strips of metal and having a run-out table for conveying the strips away from said mill, of a plurality of other tables arranged at right angles to said first named table, and switching means at the junction points of said tables adapted

to intercept the strips being conveyed along said run-out table and to direct said strips 45 onto said second named tables, said switching means comprising a housing, a guide plate in said housing for guiding the strips being switched from said run-out table onto said other tables, a vertically movable switch 50 frame, a switch plate on said frame adapted to form a continuation of said guide plate and to intercept the strips being conveyed along said run-out table in one position of said frame, and an apron plate on said 55 frame adapted to form a continuation of the top apron plate of said table in the other position of said frame.

6. The combination with a rolling mill for rolling flexible strips of metal and having a run-out table for conveying the strips away 60 from said mill, of a plurality of other tables arranged at right angles to said first named table, and switching means at the junction points of said tables adapted to intercept 65 the strips being conveyed along said run-out table and to direct said strips onto said second named tables, said switching means comprising a housing, a guide plate in said housing for guiding the strips being switched 70 from said run-out table onto said other tables, a vertically movable switch frame, a switch plate on said frame adapted to form a continuation of said guide plate and to intercept the strips being conveyed along 75 said run-out table in one position of said frame, an apron plate on said frame adapted to form a continuation of the top apron plate of said table in the other position of said frame, and pinch rollers at spaced intervals along said guide plate for conveying said strips along said plate.

In testimony whereof, I have hereunto signed my name.

HOWARD G. McILVRIED.
